(57) **CLAIM**

The ornamental design for a water bottle filler, as shown and described.

DESCRIPTION

FIG. 1 is a perspective view of a water bottle filler showing my new design;

FIG. 2 is a front elevational of the water bottle filler seen in FIG. 1;

FIG. 3 is a back elevational view of the water bottle filler seen in FIG. 1;

FIG. 4 is a left side elevational view of the water bottle filler seen in FIG. 1;

FIG. 5 is a right side elevational view of the water bottle filler seen in FIG. 1;

FIG. 6 is a top plan view of the water bottle filler seen in FIG. 1; and,

FIG. 7 is a bottom plan view of the water bottle filler seen in FIG. 1.

In the drawings, the broken lines depict portions of the water bottle filler that form no part of the claimed design.
